UNITED STATES PATENT OFFICE.

ALFRED GRIEB, OF ELIZABETH, NEW JERSEY, ASSIGNOR TO THE SINGER MANUFACTURING COMPANY, OF ELIZABETH, NEW JERSEY, A CORPORATION OF NEW JERSEY.

SEWING-MACHINE LOOP TAKER.

Application filed January 14, 1922. Serial No. 529,112.

To all whom it may concern:

- Be it known that I, ALFRED GRIEB, a citizen of the United States, residing at Elizabeth, in the county of Union and State of New Jersey, have invented certain new and useful Improvements in Sewing-Machine Loop Takers, of which the following is a specification, reference being had therein to the accompanying drawings.
- 10 This invention relates to sewing machine loop-takers generally, and more particularly to loop-takers of the rotary type adapted for cooperation with a reciprocating eye-pointed needle to form stitches.
- 15 Heretofore, it has been the usual custom to fashion a loop-taker of this character from a solid piece of material, such as a drop forging; considerable time and effort being required to machine or finish such 20 piece or forging to the requisite shape and size for efficient operation.
- While efforts have been made to fashion sewing machine loop-takers from sheet-metal blanks, such loop-takers have been unsatisfactory for the reason that they were 25 easily broken from their supports and were not so shaped as to control the needle-thread loop to the best advantage. Furthermore, with prior sheet-metal loop-takers, it has required painstaking care to center a loop-taker on its support and to set the loop-taker body in correct angular relation with the 30 axis of rotation of the loop-taker support or shaft.
- 35 An object of the present invention is to provide a sheet-metal loop-taker which retains the advantages of strength, durability, and superior sewing qualities of the more expensive loop-takers fashioned from solid 40 chunks of material or drop forgings, and which may be manufactured at low cost.
- Further objects of the invention will appear from the following description and claims.
- 45 To the attainment of the ends in view, a sheet-metal blank of predetermined shape including body and ear portions, is so bent as to dispose the ear portion in a plane parallel to the plane of action of the loop-taker body. If the body-portion includes wing

and blade portions, as in the case of a loop-taker or looper of the rotary chain-stitch type, the blade portion is twisted at an angle to the wing portion so as to lie substantially parallel to the plane of the ear portion. The 55 line of fold between the ear and wing portions is preferably disposed at the side of the center of rotation of the looper, so that such center of rotation may be located on the ear portion and marked with a hole, if so 60 desired.

A shank element is preferably turned out of ordinary round stock and may be formed with an enlarged disk-like head from the center of which projects a pin adapted to 65 enter the centering aperture in the ear portion of the looper. This pin may be swelled or headed over to secure the looper to its shank and an additional fastening may be provided by riveting or spot welding the 70 ear portion of the looper to the disk-like head of its shank at a point spaced from the center of rotation. The round shank may then be flattened along one side, as usual, to insure the proper timing of the looper when 75 mounted in the usual sewing machine looper-shaft.

In the accompanying drawings, Fig. 1 is a side elevation of a looper embodying the invention. Fig. 2 is an edge view of the 80 same looking in a direction opposite to the direction of feed. Fig. 3 is a similar view looking in the direction of feed. Fig. 4 is a bottom plan view of the looper. Fig. 5 is a disassembled top plan view of the looper 85 and Fig. 6 represents the sheet-metal blank from which the looper is made.

In the preferred embodiment of the invention, as illustrated, a blank having the form illustrated in Fig. 6 is bent along the 90 line 1 to form the fold 2 joining the ear section 3 and wing section 4. The blank is also bent in the opposite direction along the line 5, Fig. 6, to form the fold 6, Figs. 1 and 2, joining the wing section 4 and blade section 7. The blade section is formed with the loop-seizing beak 8 and loop-detaining or let-off point 9 and is twisted to position said beak and point substantially in a plane p^2-p^2 parallel to and spaced from the plane 100

p^1-p^1 of the ear section 3. It will be noted that the looper blank is formed with a slot 7^a preferably of arcuate form, separating the blade portion 7 from the wing portion 3 and defining the form of the loop-seizing beak 8. The angular relation of the wing and ear sections of the looper is preferably somewhat less than 90° in order that the line of fold 2 may be at the side of and not co-incident with the center of rotation of the looper-beak, whereby such center will fall upon the ear section 3 and may be marked with a centering aperture 10, Fig. 5. The looper-shanks 11 may be inexpensively made 15 from ordinary round stock on automatic screw machines and are each preferably formed with a disk-like head 12 the face of which is perpendicular to the axis of the shank 11 and from the center of which face projects the centering pin 13. The looper and its shank may be quickly assembled and accurately centered relatively to one another by merely placing the pin 13 in the aperture 10; said pin 13 preferably being subsequently swelled or headed over to hold the looper and shank in assembled relation. An additional fastening in the form of a rivet 14 or a spot weld may be made at a point spaced from the centering pin 13. The ear 20 section 3 adjoining the wing section 4 insures not only the correct and easy centering of the looper-blade but also the correct angular position of such blade relative to its axis of rotation. The shank 11 may be flattened, as at 15, for the end of the fastening screw 16 in the looper-supporting shaft 17, to insure correct timing of the looper relative to the reciprocating needle *n* and other cooperative elements of the machine. 25 The outer radially disposed edge of the blade-section 7 is curved or formed with a dip 18 defining a throat 19 which serves to detain the outer limb of the needle-loop 20 as the looper-beak is seizing the new needle-loop 21. By relatively bending the ear and wing sections 3 and 4, respectively, so that their angular relation to one another is less than 90°, the loop-controlling throat 19 is carried to a position approximately below the center of rotation of the looper when the looper-beak is in loop-seizing position, Fig. 30 1. This position of the throat 19 below the center 13, when the beak 8 is seizing a needle-loop, insures that the throat will, at that time, be moving along the bottom of its circular path or substantially only horizontally or parallel to the work *w*, and will therefore not slacken the previous needle-loop 20 until the looper-beak has turned a substantial angle beyond loop-seizing position and has seized the loop 21 and passed safely into the previous loop 20.

Having thus set forth the nature of the invention, what I claim herein is—

65 1. A rotary chain-stitch looper compris-

ing a body fashioned from a sheet-metal blank and shaped and bent to form a loop-seizing beak, a loop-spreading wing, and an ear adjoining said wing and disposed substantially parallel to and spaced from the plane of action of the loop-seizing beak, a shank element formed separately from the looper-body and adapted to be detachably secured to the looper-shaft of a sewing machine, and means for securing said ear to said shank element.

2. A rotary chain-stitch looper comprising a body fashioned from a sheet-metal blank and shaped and bent to form a loop-seizing beak, a loop-spreading wing, and an ear adjoining said wing and disposed substantially parallel to and spaced from the plane of action of the loop-seizing beak, a cylindrical shank element adapted to be detachably secured to the socketed end of the looper-shaft 80 of a sewing machine, and means for securing said ear flatwise upon the end of said shank element.

3. A rotary chain-stitch looper comprising a body fashioned from a sheet-metal blank 90 and having a loop-seizing beak, a loop-spreading wing and an ear adjoining said wing and bearing an angular relation of less than 90° to the general plane of said wing, a shank element, and means on said shank element and ear for relatively centering the looper and shank element.

4. A rotary chain-stitch looper comprising a body fashioned from a sheet-metal blank 100 and having a loop-seizing beak, a loop-spreading wing and an ear adjoining said wing, said ear and wing being relatively bent to stand at an angle of less than 90° to one another, substantially as and for the purposes specified.

5. A rotary chain-stitch looper comprising a body fashioned from a sheet-metal blank and having a loop-seizing beak, a loop-spreading wing and an ear bent out of the plane of said wing and disposed substantially parallel to the plane of action of said loop-seizing beak.

6. A sheet-metal rotary chain-stitch looper blank having blade, wing and ear portions, the blade and ear portions being separated by an arcuate slot extending inwardly from the edge of said blank, and the blade portion being formed with loop-seizing and let-off points.

7. A sewing machine looper of the rotary chain-stitch type comprising, a shank formed at one end with a flange and a centering pin extending centrally of and beyond the face of said flange, and a looper body fashioned from a sheet-metal blank and having blade and wing portions and an apertured ear portion standing at an angle to the wing portion and entered by said centering pin.

8. A rotary chain-stitch looper comprising

a turned shank adapted to be detachably secured to the looper-shaft of a sewing machine and formed at one end with a flange, and a looper body formed of sheet-metal and having a loop-seizing beak and a loop-spreading wing, said wing having an extension bent out of the plane of the wing and

into a plane substantially parallel with the plane of the path of movement of the loop-seizing beak, and means for securing said extension to the face of said flange.

In testimony whereof, I have signed my name to this specification.

ALFRED GRIEB.
